UNITED STATES PATENT OFFICE.

CARLETON ELLIS, OF MONTCLAIR, NEW JERSEY, ASSIGNOR, BY MESNE ASSIGNMENTS, TO SURFACE COMBUSTION, INC., OF WILMINGTON, DELAWARE, A CORPORATION OF DELAWARE.

APPARATUS FOR SUPPLYING HEAT.

Original application filed November 4, 1912, Serial No. 729,316. Divided and this application filed August 9, 1917. Serial No. 185,390. Renewed January 31, 1923.

To all whom it may concern:

Be it known that I, CARLETON ELLIS, a citizen of the United States, residing at Montclair, in the county of Essex and State 5 of New Jersey, have invented certain new and useful Improvements in Apparatus for Supplying Heat, fully described and represented in the following specification and the accompanying drawings, forming a part of 10 the same.

This invention relates to burners or apparatus for the development and supply of heat by the burning of explosive gaseous mixtures. More particularly the invention 15 has to do with burners of that class in which a granular bed of refractory material is provided into which the explosive gaseous mixture is injected with a velocity in excess of the speed of backfiring, the mixture being 20 caused to spread out and have its velocity rapidly reduced as it advances through the bed until it reaches a surface or zone at which the velocity of the mixture equals the rate of backfiring and at which surface 25 or zone combustion takes place, the combustion being thus localized within or at the surface of the bed, as more fully described in U. S. patents of Lucke No. 755,376, and of Bone, Wilson & McCourt No. 1,015,261.

30 The object of the present invention is to secure substantial uniformity of heating over the working face of the combustion bed of such a burner of considerable superficial extent, and for this purpose, in accordance 35 with the present invention, the explosive mixture is injected into the combustion bed through a plurality of apertures spaced apart at suitable distances between centers to so distribute the mixture through the bed 40 as to secure the desired substantially uniform heating thereof.

The invention is capable of general application, and is well adapted to furnaces for heating sheets or plates or other articles fed 45 through the furnace chamber past the burner or burners, as for example, a furnace such as is shown in U. S. Patent No. 1,238,011 granted on my application Serial No. 729,316, filed November 4, 1912, of which 50 this application is a division.

In the accompanying drawings:—

Fig. 1 is a somewhat diagrammatic sec-

tional elevation of the sheet heating furnace illustrated in my said application No. 729,316;

55

Fig. 2 is an enlarged sectional view of one of the heating devices or burners;

Fig. 3 is a plan view of the burner shown in Fig. 2;

Fig. 4 is a diagrammatic view on a larger 60 scale illustrating an arrangement of injecting apertures and heat zones; and

Fig. 5 is a corresponding enlarged sectional view through a part of the combustion bed.

65

Referring to the drawings, the furnace as illustrated comprises a suitable furnace chamber 1 having walls of refractory material and provided with a flue connection 10 adjacent one end. A suitable conveyor 2 70 is arranged to pass through the furnace to carry steel plates or other articles 3, being shown as mounted on and driven by sprocket wheels 4 and 5. Swinging doors or gates 11 and 12 are provided at the ends of the furnace chamber to cooperate with the conveyor and make more or less tight joints while permitting the passage of the conveyor and articles carried thereby.

75

The burners or heating devices comprise 80 combustion beds of granular material mounted with their working faces closely adjacent the path of the articles on the conveyor. The explosive gaseous mixture is injected into each of these combustion beds 85 through a plurality of injecting orifices so that combustion takes place as described in the Lucke and Bone, Wilson & McCourt patents before referred to, that is, the explosive gaseous mixture entering the refractory bed with a velocity in excess of the speed of backfiring is caused to spread out 90 and have its velocity rapidly reduced as it advances through the bed until it reaches a surface or zone at which the velocity of the mixture equals the rate of backfiring and at which surface or zone combustion takes 95 place, the combustion being thus localized within or at the surface of the bed. The lower bed 8 may be formed of substantially uniformly sized granules of refractory material such as alumina, magnesite, or even refractory fireclay for the lower heats, of, 100 for example, about one-half or three-quarter

95

100

inch mesh and arranged within a suitable refractory lining 6 so that the upper or working face of the bed which is heated to incandescence under operating conditions is 5 preferably relatively closer than indicated in Fig. 1 of the drawing to the articles to be heated and arranged within a few inches of the path of the articles for most rapid work. The upper combustion bed 28, if 10 provided, may also be formed of granules of refractory material permanently secured in position in the refractory bed lining 26 as by coating the particles with a small amount of relatively fusible or fluxing material and 15 then calcining the bed and lining at an intensely high temperature so as to cause the refractory granules to permanently unite together and to the bed lining by fusing or fluxing together their contacting portions at 20 heats considerably in excess of any working temperatures to which they are subsequently subjected. In this way, as indicated in Figs. 1 and 5, the granules are permanently secured together in such way as to leave 25 numerous tortuous passages between them substantially similar to the passages through a bed of loose granules.

These porous and permeable beds are 30 heated by injecting thereinto an explosive gaseous mixture which may be formed of combustible gas or vapor and air or other supporter of combustion preferably in about the proportions required to secure complete combustion of the fuel for greatest efficiency, 35 although by using a slight excess of the fuel gas a slightly reducing atmosphere may be maintained in the furnace to avoid oxidation. The explosive gaseous mixture is injected into the combustion bed through a 40 plurality of injecting apertures provided by nozzles or short pipes 13 spaced preferably uniformly throughout the bed to secure uniformity of heating, these injecting nozzles or apertures being preferably so spaced as 45 to secure sufficient overlapping or approximation of the heat zones produced by the mixture supplied from each of the apertures as to secure substantial uniformity of heating throughout the bed, such uniformity of 50 heating being highly desirable for many purposes, and especially in heating thin plates or other articles in a furnace of the kind illustrated by Fig. 1. For moderate sized injecting apertures of, for example, 55 three-eights of an inch to an inch or so in diameter, through which is injected an explosive mixture formed from coal gas or enriched producer gas and air at a pound or so pressure, which gives sufficient velocity to 60 prevent backfiring through the injecting apertures, the spacing of the apertures and thickness of the granular bed to give a most effective and uniform heat should apparently, as determined by an extended series of 65 empirical tests, bear about such ratio to the

size of the apertures that $D=4A$ and $C=2D=8A$; where D is the depth of the granular bed, A is the diameter of the injecting apertures and C the distance between the centers of the apertures; that is, the distance between the center lines of adjacent apertures as indicated in Figs. 4 and 5. Under these circumstances, the heating zones extending from the several apertures, while of course somewhat irregular because of the tortuous character and irregular section of the channels through the granular bed, have approximately such boundaries as indicated by the lines 14-14 in Figs. 3, 4 and 5, so that there tends to be some overlapping in the areas 15 where the heating zones approach most closely, although these reinforced areas are naturally equalized to a considerable extent by the action of the gas pressure within the granular bed. A substantially uniform temperature and substantially uniform incandescence is thus secured throughout the working face of a porous and permeable bed of this character; and as in a bed of this character unusual quantities of gaseous fuel may be burned in a very restricted space, the rate of combustion being accelerated many times beyond that occurring in ordinary flame combustion, extremely rapid as well as uniform 95 heating may be effected because of the extremely high temperatures secured in the working face of the bed and the correspondingly great radiating efficiency thereof. This is of great importance, especially in a conveyor furnace such as shown.

The explosive gaseous mixture may be supplied to the combustion bed by any suitable arrangement, such for example, as the supply pipes 7 shown in Figs. 1, 2 and 3 as 105 connecting the lines of injecting nozzles 13; and these supply pipes may be connected to a suitable supply line as 17 fed with explosive gaseous mixture which may be supplied under the desired pressure by any suitable 110 form of pump or other device. The supply line may, as indicated, have a suitable Y connection, the air connection 18 leading to a suitable air pump 19 and receiving therefrom air under pressure which has been 115 drawn from the air line 20. The gas connection 21 similarly receives the combustible gas or vapor from a gas pump 22 which draws the gas from a gas line 23, so that in this way a substantially uniform explosive 120 mixture of gas and air can be conveniently secured, the mixture preferably containing a slight excess of gas where steel plates or other steel articles are to be heated so as to maintain a slight reducing atmosphere 125 within the hot portion of the furnace and minimize oxidation of the metal.

The plates or articles 3 fed along by the conveyor in the furnace shown in Fig. 1 between the heating devices or burners are 130

very rapidly and highly heated as they come between the beds, especially by the radiant heat from the highly incandescent working faces of the beds. It is thus not only possible to secure a rapid and uniform heating of the articles, but because of the easy regulation and control of the mixture supply and the amount of fuel burned in the beds, it is possible to accurately time the feed or supply of the heated articles as may be desired, as for example, in supplying the articles to a press or forging device so as to secure the most satisfactory results from uniformity of the forging or stamping conditions. By conducting the intensely hot combustion gases along the furnace chamber in the opposite direction to the articles fed toward the combustion beds a considerable preheating action can be secured depending upon the length of the furnace chamber, and a corresponding economy in fuel consumption thus effected.

By the term "explosive gaseous mixture" as used herein is meant a mixture of a suitable combustion supporting gas, either oxygen alone or air or other oxygen containing gas, with combustible matter in a gaseous or other finely divided state in proportions such that the mixture will have the property of self-propagation of inflammation. Such proportions may be the chemical combining proportions or there may, of course, be an excess of either the combustible matter or the combustion supporting gas within the limits which determine the property of self-propagation. The mixture may be varied in this respect according to the

desired character of the products of combustion.

Having described the invention in connection with an illustrative embodiment thereof, to the details of which disclosure the invention is not to be limited, what is claimed as new is set forth in the appended claims.

What is claimed is:

1. Heating apparatus comprising a porous and permeable bed of refractory material, and means providing a plurality of apertures for injecting an explosive gaseous mixture into said bed with a velocity in excess of the speed of backfiring of the mixture, said apertures being spaced apart to so distribute the mixture through the bed as to secure substantially uniform heating thereof.

2. Heating apparatus, comprising a porous and permeable bed of refractory material, means providing a plurality of apertures for injecting an explosive gaseous mixture into said bed, and means for supplying the mixture under pressure sufficient to cause the mixture to be injected into the bed with a velocity in excess of the speed of backfiring of the mixture, said apertures being spaced apart to so distribute the mixture through the bed as to secure substantially uniform heating thereof.

In testimony whereof I have hereunto set my hand in the presence of two subscribing witnessses.

CARLETON ELLIS.
